HEEL-BUILDING MACHINE.

1,080,682.

Specification of Letters Patent.

Patented Dec. 9, 1913.

Application filed December 19, 1910. Serial No. 598,080.

To all whom it may concern:

Be it known that I, GEORGE A. DOBYNE, a citizen of the United States, and residing at St. Louis, in the State of Missouri, have invented certain new and useful Improvements in Heel-Building Machines, of which the following is a specification.

This invention relates to machines for building heels.

10. Heels are generally built up of lifts which are cut from scrap and waste material. In the utilization of such scrap, not only is the heel made up of layers, but the separate layers are built up of pieces. These pieces 15. are pasted together and temporarily secured together by means of one or more fasteners, and then the assembled lifts are placed in a press and left to dry. Such a press is able to accommodate a large number of assembled heels, the heels being piled in the press and the whole being subjected to pressure until dry or nearly dry. The pieces of scrap are entirely too irregular and ununiform 20. in shape to be automatically assembled by mechanism, and therefore the assembling must be done by hand. In order that the method of building heels from scrap or waste leather may be used economically, the apparatus must be so arranged that the lifts 25. 30. can be assembled rapidly and by unskilled operators. In apparatus which has been heretofore used to a small extent, the lifts were assembled in a mold and then secured by a fastener. Such an apparatus, however, 35. rendered the method entirely too slow to be used economically for the following reasons: Where the lifts are assembled in a mold, these lifts must be inserted in a "hole", which necessitates that each lift or piece be 40. dropped in place and the operator cannot therefore use both hands at once for placing the lifts in position, since the small space in the mold will not permit such operation. The result is that the assembling operation 45. 50. has been performed heretofore to a large extent by assembling the lifts against a small gage on a table, and the fastener was also driven by hand. This is, of course, an exceedingly slow and expensive method and requires that the operators first assemble the heel by hand, and then pick up a hammer and drive the fastener.

One of the objects of this invention therefore is to construct a machine in which the lifts can be rapidly assembled and fastened

together, the positioning means whereby the lifts are assembled being so constructed that the operator can use both hands at once to place the lifts in position from opposite sides.

Another object is to construct a machine in which as much of the operation as possible will be automatic, leaving the operator's hands free at all times to assemble the lifts.

Another object is to construct the machine so that the lifts may be automatically fastened together when assembled, and clamped while being fastened.

Another object is to construct the machine so that the use of the necessary paste will not clog up and interfere with the bearings and guides, and to arrange the elements of the mechanism so that wear and friction will be reduced to a minimum.

Further objects will appear from the detail description taken in connection with the accompanying drawings in which:

Figure 1 is a side elevation partly in section showing one embodiment of this invention, Fig. 2 is a front elevation, Fig. 3 is a plan, Fig. 4 is a detail section on the line 4-4 Fig. 1, and Fig. 5 is a detail of the clutch mechanism.

In accordance with this invention the lifts are assembled on a support or table against a suitable gage or positioning stop. After the lifts are thus assembled a fastener inserting mechanism is moved into operative relation with respect to the assembled lifts 85 to drive a fastener therein. The operation after the lifts have been assembled is preferably entirely automatic, the fastener inserting mechanism being moved into position automatically upon the depression of a starting lever or treadle, a fastener being driven, and the fastener inserting mechanism being automatically returned to initial inoperative relation away from the lifts so as to clear these assembled lifts and permit the finished heel blank to be removed and another one assembled. The table and positioning means are so constructed that the table forwardly of the gage and stop, and laterally of and above the portion of the table occupied by the assembled lifts, is entirely clear from all obstructions permitting the lifts to be moved to assembled position from opposite sides.

Referring to the accompanying drawings,

10 designates a suitable support or table, and 11 a breast gage or stop which is adjustably mounted on the table and arranged to be locked in adjusted position by means 5 of a clamping screw 12 engaging a slot in the gage. The gage is preferably provided with graduations (not shown) forming a scale for the height of the assembled heel blank. A pair of guides 13 are mounted on 10 the table so as to slidably support a carrier or head 14 thereon. The front face 15 of this carrier is machined to receive a nail block or throat piece 16 which is arranged to be adjusted vertically on the head by being 15 mounted in suitable guides thereon, and arranged to be clamped in adjusted position by means of clamping screws 17 extending through slots cut in the flanges 18 on the block and threaded into tapped holes in the 20 front face of the carrier. A driver bar 19 is supported and guided in bearings 20 formed on the carrier, and this driver bar has secured thereto a driver 21 which works in a driver passage cut in the nail block. A 25 cam roll 22 on the driver bar is engaged by a driver cam 23 of well known construction which is secured to and driven by a shaft 24 mounted in bearings formed in the head. The upper end 25 of the driver bar is en- 30 gaged by a lever 26 which is under the tension of a spring 27. The driver 21 is clamped in the driver bar in the usual manner by means of a set screw 28 so that the driver may be adjusted with respect to and 35 with the nail block by adjusting the driver in the driver bar. The lower limit of the stroke of the driver may also be varied by adjusting the collar 29 on the bar 19 in any suitable manner. Such adjustments are well 40 known and need not be described in detail.

A clamp or lift engaging member 31 is supported by the carrier underneath the nail block. This clamp is provided with a pair of shanks 32 guided in the carrier and 45 provided with coiled springs tending normally to force the clamp away from the carrier. The outward movement of the clamp is limited by a pin or screw 34 engaging a slot in one shank. The forward 50 face of the clamp is rounded and beveled to conform to the backs of the assembled lifts, and this rounded face may if desired be lined with any suitable soft and elastic material such as rubber. The pin 34 is re- 55 movable so that the clamp 31 can be removed and another one of a different height substituted.

A pedestal 35 is bolted on the table and provided with bearings for a main driving 60 shaft 36 which has loosely mounted thereon a belt pulley 37. A jaw clutch is arranged to clutch the shaft with the pulley and comprises a jaw 38 secured to the pulley, and a coöperating jaw 39 splined on the shaft 65 and pressed into engagement with the jaw

38 by means of a spring 40. A pin 41 on the jaw 39 is arranged to be engaged by a clutch lever 42 which is pivoted at 43 and is under the tension of a spring 44 tending to move it in a counter-clockwise direction Fig. 5. A pin or lug 45 connected to the lever 42 is arranged to be engaged by a toe 46 on a treadle operated rod 47, which is mounted in a bearing 48 on the pedestal 35 and is normally moved downward by a spring 49. A pin or lug 50 on the pedestal 35 is arranged to be engaged by a cam lug 51 on the rod 47. The rod 47 is mounted for lateral movement in the guide 48 and normally maintained in the position shown 80 by means of a leaf spring 48a.

The clutch above described is of the single revolution type and is arranged to automatically stop the shaft after one revolution is completed, whether the treadle is released or is maintained in depressed position. The operation will be obvious. As the treadle rod 47 is raised, the clutch lever 42 will be moved in a clockwise direction so as to release the pin 41 and permit the 90 clutch jaws to engage. During the upward movement of the treadle rod, the engagement of the cam lug 51 with the fixed pin 50 will move the treadle rod laterally so as to move the toe 46 out of engagement with the cam 45 releasing the clutch lever, which under the action of its spring will be thrown inwardly, so that the pin 41 will be engaged by the cam on the clutch lever, causing the clutch jaws to be thrown out of engagement 95 and the shaft 36 arrested after one revolution has been completed. When the treadle is again released the toe 46 will snap over the pin 45 and will return to initial position 100 as shown in the drawings.

The shaft 24 has an extension 52 which has a splined connection with the shaft 36 as shown in Fig. 1, whereby the carrier may be moved axially of the shaft without breaking the driving connection. A cam 53 is secured to the shaft 24 in a recess in the head or carrier. This cam is provided with a cam groove 54, of substantially the form shown in the drawings, which is engaged by a cam roll mounted in the arm 55 of a double 115 armed lever journaled at 56 on the head. The other arm 57 of the lever has a pivotal connection with one end of a link 58 the other end of which is pivoted at 59 to the pedestal 35.

Nail loading and feeding mechanism of usual construction is supported on the pedestal 35 and comprises a rotating nail loading drum, a raceway and a nail separator. The main casing of the nail loader 125 is indicated at 60 and is shown as provided with a filling hopper 61. A drum 62 is provided with the usual nail elevators and with a shaft which is driven from the shaft 36 by means of a belt 63 passing over pulleys 130

64 and 65 on the drum and main driving shaft respectively. A raceway 66 of usual construction extends into the loader casing and is supported thereby, and is provided at its lower end with a nail passage and a separator 67 arranged to feed the nails one by one to the nail passage. The separator is moved in one direction by means of a spring 68 and in the opposite direction by means of a cam lug 70 on the cam 53 engaging the end 69 of the separator. This separator is of ordinary construction and operates when the carrier or head returns to its initial or rearward position, as hereinafter described, to feed a fastener to the funnel shaped end of a nail tube 71 which guides the fastener to the driver passage. The nail tube is preferably of flexible construction so as to be adjustable with the nail block in a manner well known to those skilled in the art.

The operation of the machine will now be described.

When the machine is at rest with the driving shaft disconnected, the head or carrier is in rearward position away from the gage 11 and the parts will be in the position shown in the drawings. The driver is at this time in depressed position, and the last rearward movement of the carrier will have actuated the separator to drop a nail in the nail tube 71, and this nail will be resting against the side face of the driver. If there is no nail in the nail tube then the separator can initially be operated manually to release a single nail. After the lifts have been positioned in assembled relation against the gage 11, the treadle is depressed so as to operate the clutch in the manner described. The cam 53 will now coöperate through the lever and link connection with the rigid abutment 59 to move the entire carrier forwardly with the nail block over the assembled lifts. This will cause the yieldingly mounted clamp 31 to engage the back of the lifts and firmly clamp the lifts together. After the carrier has been moved to forward position, it will remain at rest during a half revolution of the shaft, and during this half revolution the cam 23 will operate to raise and release the driver. The nail or fastener which rests against the driver drops into the driver passage or throat piece as the driver is raised, and is driven in the assembled lifts by the descent of the driver. During the next quarter revolution the carrier is returned to initial position away from the assembled lifts, and as the carrier nears the initial position, the separator will be engaged by the cam lug 70 to separate and drop another nail into the nail tube. The driving shaft 36 will at the end of the revolution be automatically arrested and the parts will come to rest with the carrier in initial position, with the

driver down, and a separated nail resting against the driver. It will be understood that during the revolution of the shaft the nail loader has been operated to load nails or fasteners in the raceway.

In the operation of assembling and securing the assembled lifts together, the lifts will be piled on the table and against gage 11 from right and left. Preferably paste or cement brushes B driven by a pulley b are also mounted on the table, and these brushes may run continuously in paste receptacles C below the top of the table as shown in the drawings. The operator will stand in front of the table and pile the lifts in place using both hands. In assembling he will pass the lifts over the brushes B to apply a coating of cement or paste thereto, and then move them to assembled position from the sides. Naturally in quick operation the movement of the lift from the time it is picked up until it is placed in position will be practically a continuous sideward movement, the lifts being quickly passed over the brush and by continuous movement against the breast gage. This is possible in view of the fact that the table, in front of, laterally of and above the gage, is entirely clear; the assembling can therefore be performed very rapidly. After the lifts have been assembled, the fastener inserting mechanism is moved into and out of operative position above the assembled lifts automatically. In the movement of the carrier toward the gage 11, the clamp 31 will first yieldingly engage the backs of the lifts, and the fastener is driven while the lifts are thus clamped between the breast gage 11 and the clamp 31. This insures that the cemented joints will be firm and prevents the assembled lifts from being shattered apart while the fastener is driven. The hands of the operator are free at all times, and it is not necessary for him to stop and pick up a hammer and drive a long fastener. This is quite an advantage, in view of the fact that the operator's hands are covered with paste rendering the manipulation of the hammer and nail exceedingly difficult where the fastening operation is performed by hand, and in addition saving an immense amount of time. The only real manual operation is the assembling, the fastening operation and the return of the carrier being performed automatically upon depression of the treadle.

In order to adjust the machine for heels of different sizes, the breast gage can be adjusted on the table, and the nail block together with the driver can also be adjusted toward and from the table. The adjustment for varying the relation of driving mechanism and the breast gage need merely be a relative adjustment, and therefore the adjustment may be in the link 58 or in some

other part of the connection of the carriage with the rigid abutment 59. However, by adjusting the breast gage, not only may the adjustments be very much simplified, but the connections driving the carrier can be fixed and permanent connections, so that the carrier has a fixed stroke. It will be noted that the back gage 31 is automatically adjusted with respect to both the fastener inserting mechanism and the breast gage. The cams 23 and 53 are so proportioned and timed that the driver is operated while the carrier is at rest. By means of this construction there is no torsional strain on the splined connection between the shafts 24 and 36 during the movement of the carrier into and out of operative position, which not only results in a decrease of wear of the parts, but also in a decrease of frictional resistance so that the parts may be made lighter throughout. The actuating means for the driver and the operating means for moving the carrier into and out of position are, therefore, so arranged that one is in operative action while the other is out of operative action. The driver comes to rest in depressed position. This is advantageous in view of the fact that it lengthens the life of the driver spring. This also enables the feeding mechanism for the fasteners to be simplified when using a stationary nail loader and feeder.

It will be noted that the positioning gage 11 which positions the lifts in assembled relation remains with the assembled lifts at rest, while the fastener inserting mechanism is movable into and out of position above the lifts. This has many advantages over a construction in which the assembled lifts are moved underneath the fastener inserting mechanism. By means of this construction the table laterally of the assembling portion or space is left entirely clear and smooth; the assembling can therefore be performed quickly. There are no guides to be clogged up with paste. The lifts are better supported and are better maintained in assembled relation after they are once assembled since they remain at rest. Where the assembled lifts are moved quickly to position the inertia effect is liable to work to a disadvantage in shaking the assembled lifts loose. In the present construction after the lifts have been assembled the operator can maintain them in position by placing his fingers upon opposite sides of the assembled lifts while they are being fastened.

In the specific embodiment shown the stationary gage is the breast gage while the other one is the back gage. While this is the most advantageous construction it will be obvious that the positions of these gages may be reversed. It is also obvious that various changes may be made in the details of construction without departing from the

spirit of this invention, and it is therefore to be understood that this invention is not to be limited to the specific construction shown and described.

Having thus described the invention what is claimed is:

1. In a heel building machine, the combination of a table forming a stationary support for the lifts, a gage on said table for positioning the lifts in assembled relation on a portion of said table, fastener inserting mechanism, and automatic means for moving said fastener inserting mechanism into position over the assembled lifts to drive a fastener, and away from and clear of said portion and gage to permit the lifts to be assembled. 75 80

2. In a heel building machine, the combination of a table forming a stationary support for the lifts, a gage on said table for positioning the lifts in assembled relation on a portion of said table, fastener inserting mechanism including a driver, means for automatically loading and feeding a fastener to said driver, and automatic means for moving said fastener inserting mechanism into position over the assembled lifts to drive a fastener so fed to the driver, and away from and clear of said portion and gage to permit the lifts to be assembled. 85 90 95

3. In a heel building machine, the combination of a table having a stationary lift supporting portion and a gage for positioning the lifts in assembled relation thereon, the table laterally of said portion being clear, fastener inserting mechanism, and means operating automatically to move said fastener inserting mechanism over the assembled lifts to drive a fastener, and away from the supporting portion and the gage to clear said parts and permit the lifts to be assembled, said operating means being constructed to stop with the parts in the last named position. 100 105

4. In a heel building machine, the combination of a table having a stationary lift supporting portion and a gage for positioning the lifts in assembled relation thereon, fastener inserting mechanism, and means operating in succession to move the fastener inserting mechanism over the assembled lifts, drive a fastener, and to move the fastener inserting mechanism away from the supporting portion and the gage to clear said parts and permit the lifts to be assembled. 110 115 120

5. In a heel building machine, the combination of a table having stationary lift supporting and positioning means adapted to position and support the lifts in assembled relation, a clamp, power operated fastener inserting mechanism, and means whereby said clamp may be moved into engagement with the assembled lifts and the fastener inserting mechanism over the as- 125 130

sembled lifts to drive a fastener, and whereby the clamp and fastener inserting mechanism may be moved away from the supporting and positioning means to clear said parts and permit the lifts to be assembled.

6. In a heel building machine, the combination of a support or table having a stationary assembling portion, a gage on said table adapted to position the lifts in assembled relation on said portion, guides on said table, a head carrying power operated fastener inserting mechanism and movable in said guides to position the fastener inserting mechanism over the assembled lifts and movable away from said portion and gage to permit the lifts to be assembled.

7. In a heel building machine, the combination of a support or table having a stationary assembling portion, a gage on said table adapted to position the lifts in assembled relation on said portion, guides on said table, a head carrying power operated fastener inserting mechanism and movable in said guides, a clamp adapted to engage the assembled lifts and movable with said head, and means for moving said head and clamp to engage the clamp with the assembled lifts and to position the fastener inserting mechanism over the assembled lifts, and for returning said members to permit the lifts to be assembled.

8. In a heel building machine, the combination with a stationary support or table and a gage thereon adapted to position the lifts in assembled relation on said table, of a clamp adapted to engage the assembled lifts, power operated fastener inserting mechanism, and means for moving said clamp and fastener inserting mechanism together into and out of operative relation with respect to the assembled lifts.

9. In a heel building machine, the combination with a stationary support or table and a gage thereon adapted to position the lifts in assembled relation on said table, of a clamp adapted to be moved into engagement with the assembled lifts, fastener inserting mechanism movable into position over and away from the assembled lifts, and power operated means for actuating said fastener inserting mechanism to drive a fastener while over the lifts and while the assembled lifts are engaged by said clamp.

10. In a heel building machine, the combination with a support, of lift engaging members thereon movable toward and from each other and adapted to assemble and clamp the lifts in assembled relation, and power operated fastener inserting mechanism movable with one of said lift engaging members toward and from the other.

11. In a heel building machine, the combination with a support, of co-operating lift engaging members thereon adapted to engage the breast and back of the lifts and

clamp them in assembled relation, and power operated fastener inserting mechanism movable with one of said members toward and from the other.

12. In a heel building machine, the combination with a support or table and a gage thereon adapted to position the lifts in assembled relation on said table, of fastener inserting mechanism, means having a fixed stroke for moving said fastener inserting mechanism toward and from said gage and into and out of position over the assembled lifts, means for operating said fastener inserting mechanism to drive a fastener when said fastener inserting mechanism is in position over the assembled lifts, and means permitting adjustment of said gage toward and from said fastener inserting mechanism.

13. In a heel building machine, the combination with a support, of co-operating lift engaging members thereon adapted to engage the lifts and clamp them in assembled relation, power operated fastener inserting mechanism movable with one of said members toward and from the other, and means permitting adjustment of the last mentioned member relatively to the fastener inserting mechanism.

14. In a heel building machine, the combination with a support, of a gage thereon adapted to position the lifts in assembled relation, a clamp adapted to engage the assembled lifts, power operated fastener inserting mechanism movable into and out of operative relation with respect to the assembled lifts, and an operator for said clamp and said fastener inserting mechanism having a yielding connection with the clamp.

15. In a heel building machine, the combination with a support, of a gage thereon adapted to position the lifts in assembled relation, a clamp adapted to engage the assembled lifts, power operated fastener inserting mechanism movable into and out of operative relation with respect to the assembled lifts, said clamp having a yielding connection with said fastener inserting mechanism and being movable therewith.

16. In a heel building machine, the combination with a support, of a gage thereon adapted to position the lifts in assembled relation, power operated fastener inserting mechanism movable toward and from said gage, a clamp adapted to engage the assembled lifts, and a yielding connection between said fastener inserting mechanism and said clamp whereby said clamp is moved by said mechanism.

17. In a heel building machine, the combination with a support, of a gage thereon adapted to position the lifts in assembled relation, a clamp and power operated fastener inserting mechanism, and operating mechanism adapted to move the clamp into

yielding engagement with the lifts and the fastener inserting mechanism over the lifts and drive a fastener while the lifts are clamped.

5 18. In a heel building machine, the combination with a support, of a stationary breast gage thereon adapted to position the lifts in assembled relation, a yieldingly mounted member movable toward and from 10 said breast gage and adapted to engage the back of the assembled lifts, and power operated fastener inserting mechanism movable over the assembled lifts as positioned by said breast gage to drive a fastener therein, and movable away from and clear of said gage to permit lifts to be assembled.

15 19. In a heel building machine, the combination with a support or table and a fixed gage thereon adapted to position the lifts on 20 said table in assembled relation, fastener inserting mechanism, and means operating automatically in succession to move said fastener inserting mechanism over the assembled lifts, insert a fastener, and with- 25 draw said fastener inserting mechanism to permit the lifts to be assembled.

20 20. In a heel building machine, the combination with a support or table and a gage thereon adapted to position the lifts in as- 30 sembled relation on a portion of said table, of a member adapted to coöperate with said gage to clamp the lifts in assembled relation, fastener inserting mechanism, and means operating automatically and suc- 35 cessively to position said mechanism over the lifts, drive a fastener, and then move the fastener inserting mechanism away from and clear of said portion and gage to permit the lifts to be assembled.

40 21. In a heel building machine, the combination with a support and means thereon adapted to position the lifts in assembled relation, of fastener inserting mechanism having a driver, and means operating in 45 succession, to position the fastener inserting means over the assembled lifts, operate the driver to drive a fastener, and return the parts to position to clear each other with the driver in depressed position.

50 22. In a heel building machine, the combination with a support and means thereon adapted to position the lifts in assembled relation, of fastener inserting mechanism having a spring actuated driver, and means op- 55 erating in succession, to position the fastener inserting means over the assembled lifts, operate the driver to drive a fastener, and return the parts to position to clear each other with the driver in depressed position.

60 23. In a machine of the class described, the combination with lift supporting and positioning means adapted to position the lifts in assembled relation, of fastener inserting mechanism, and means operating au-

tomatically and successively to move the 65 fastener inserting mechanism over the as- sembled lifts to drive a fastener, and then placing the members at rest in initial inop- erative relation.

24. In a machine of the class described, 70 the combination with lift supporting and positioning means adapted to position the lifts in assembled relation, of fastener in- 75 serting mechanism, operating mechanism for said fastener inserting mechanism, and controlling mechanism for said operating mechanism, whereby said fastener inserting mechanism is automatically moved into op- erative position over the assembled lifts to 80 drive a fastener and then returned to initial inoperative position clear of the supporting and positioning means with the operating mechanism thrown out of action.

25. In a machine of the class described, 85 the combination with lift supporting and positioning means adapted to position the lifts in assembled relation, of fastener in- 90 serting mechanism, driving mechanism op- erating automatically and successively to move the fastener inserting mechanism over 95 the assembled lifts, drive a fastener, and back to initial position clear of the support- ing and positioning means, and automatic means to throw the driving mechanism out of action when said parts are in initial po- 95 sition.

26. In a machine of the class described, the combination with a support or table, of means adapted to position lifts in assem- 100 bled relation on said table, fastener insert- 105 ing mechanism movable into and out of op- erative relation with respect to the assem- bled lifts, said parts being constructed to leave the table portion laterally of the posi- 110 tioning means clear to permit free assem- bling of the lifts, and paste applying means mounted on said table and positioned later- ally of said lift positioning means.

27. In a machine of the class described, 110 the combination with a support or table and a gage thereon adapted to position the lifts in as assembled relation on said table, of fastener inserting mechanism movable into and out of operative relation with respect to the assem- bled lifts, said parts being constructed 115 to leave the table laterally of the portion occupied by the assembled lifts clear to per- mit the lifts to be moved into position from the side, and pasting brushes mounted on said table laterally of and on each side of 120 said gage and said portion and adapted to be engaged by the lifts as they are moved to assembled position.

28. In a machine of the class described, 125 the combination with work supporting means, of fastener inserting mechanism, a carrier for said mechanism movable toward and from the work, an actuating shaft for

said mechanism supported on and movable with said carrier, and means for reciprocating said carrier from said shaft.

29. In a machine of the class described, the combination with work supporting means, of fastener inserting mechanism including a driver, a carrier for said mechanism movable toward and from the work, an actuating shaft, and cams mounted on

said shaft and movable with said carrier, 10 one cam operating the driver and the other moving the carrier.

In testimony whereof I affix my signature in presence of two witnesses.

GEO. A. DOBYNE.
